DESIGN FOR A SAIL PROPELLED
WHEELED VEHICLELaurence D. Ely, Jr., and John M. Ely,
Daytona Beach, Fla.

Application September 26, 1946, Serial No. 133,588

Term of patent 3½ years

(Cl. D14—3)

To all whom it may concern:

Be it known that we, Laurence D. Ely, Jr., and John M. Ely, citizens of the United States, both residing at 1440 North Atlantic Avenue, Daytona Beach, in the county of Volusia, State of Florida, have invented a new, original, and ornamental Design for a Sail Propelled Wheeled Vehicle, of which the following is a specification, reference being had to the accompanying drawing, forming part thereof, wherein:

Figure 1 is a side elevational view of a sail propelled wheeled vehicle, showing our new design.

Figure 2 is a front elevational view thereof, and Figure 3 is a top plan view thereof.

The characteristic features of our design reside in the portions shown by means of full lines in the drawing.

We claim:

The ornamental design for a sail propelled

wheeled vehicle, substantially as shown and described.

LAURENCE D. ELY, JR.
JOHN M. ELY.
